UNITED STATES PATENT OFFICE.

JAMES M. HOPKINS, OF CHICAGO, ILLINOIS.

METAL CAR-DOOR.

No. 796,652.

Specification of Letters Patent.

Patented Aug. 8, 1905.

Application filed December 17, 1904. Serial No. 237,337.

To all whom it may concern:

Be it known that I, JAMES M. HOPKINS, a citizen of the United States, and a resident of Chicago, county of Cook, and State of Illinois, have invented certain new and useful Improvements in Metal Car-Doors, of which the following is a specification, and which are illustrated in the accompanying drawings, forming a part thereof.

The invention relates to a box-car door made of sheet metal, its object being to provide a simple and rigid car-door and also to reduce the thickness of the door and width of the car.

In the construction of box-cars it is regarded as of extreme importance to obtain the maximum of capacity. The width of the car in its outside measurement, or "over all," is rigidly limited by track conditions. In endeavoring to increase the capacity the inside measurement is increased to the utmost, being limited only by the restrictions as to outside measurement and the necessary thickness of the walls of the car and their appurtenances. The widest portion of a box-car is in line with its door, and it becomes necessary, therefore, to reduce the thickness of the door and the size of the trimmings as much as practicable consistent with strength and proper protection.

Heretofore car-doors have been made of wood, and hence necessarily of considerable thickness. To the surface of the door there has been added the trimmings, such as hangers, guide-blocks, &c.

The present invention comprises a door made of sheet metal and stiffened by having its margins turned or flanged, the trimmings being applied to the flat surface of the door and its flanges serving as shoulders against which they may in most instances be braced. In some of the forms of construction shown the rearward flange of the door is turned inwardly and serves as a weather-protecting strip.

In the accompanying drawings, illustrating the invention, Figure 1 is a detail side elevation of a box-car, showing the improved door. Fig. 2 is a sectional view on the line 2 2 of Fig. 1; and Figs. 3, 4, and 5 are edge views of the door, showing various modifications.

The side of the car is designated 10. The door 11 is shown as made of a single plate of sheet metal, which will be of any suitable

thickness and may in most instances be not more than one-eighth of an inch in thickness. The margins of the plate are flanged, the flange preferably being of about one-half inch in width.

As shown in Figs. 1 and 3, all of the edges 12, 13, 14, and 15, the first two being the sides and the last two the top and bottom of the door, are turned or flanged outwardly. In the construction shown in Fig. 4 the rearward edge of the door is flanged backwardly, as shown at 16, and in the construction shown in Fig. 5 this flange, as shown at 17, is represented as somewhat longer than shown at 16 and is turned backwardly and forwardly. In the former case the flange 16 coöperates with a weather strip or cleat 18, secured to the side 10 of the car along the rearward side of the door-opening, and in the latter case the hook-shaped flange 17 coöperates with an L-shaped weather-plate, (shown at 19,) which projects outwardly from the door-frame or car-body 10 and backwardly, so that the door-flange and this weather-plate interfold when the door is closed.

The door is further strengthened by means of corner-brackets 20, set within the angles of its flanges and riveted thereto and to the body of the door. The usual wedge-blocks 25, which coöperate with the guide-brackets 26 for forcing the door snugly against the side wall of a car when closed, are shown as attached to the body of the door adjacent to its bottom flange 15. The hangers for carrying the door (shown at 21 22) are riveted to the body of the door, and each is provided with a shoulder 23, which abuts against the top flange 14, whereby the weight of the door is borne largely by the flange, and the rivets, by means of which the hanger-bracket is attached, are relieved in great measure of the shearing strain that would otherwise come upon them.

The door is shown as suspended from a Z-shaped track 24, the pendent flange of which overlaps the top flange 14, the latter projecting forwardly against or substantially to its rear face, thereby forming an effectual protection against the weather without the necessity of added weather-strips, as air-currents will be naturally deflected outwardly by the contour of the door itself.

When the door is closed, the front flange 12 will lie flat against the door-stop strip 27,

forming therewith a close joint. Any form of hasp or other locking device may be applied as desired.

I claim as my invention—

1. A box-car door formed of sheet metal and having its edges flanged, the front and top and bottom flanges being turned outwardly and the rear flange being turned inwardly.

2. A box-car door formed of sheet metal and having its edges flanged, the front and top and bottom flanges being turned outwardly and the rear flange being turned inwardly and bent forwardly.

3. A box-car door formed of sheet metal having its top edge flanged outwardly; hanger-brackets secured to the body of the door and abutting against the top flange thereof.

4. In combination, a sheet-metal door hav-

ing its top edge flanged outwardly; and a track for carrying the door and having a pendent flange overhanging the top edge of the door.

5. In combination, a sheet-metal door having its top, bottom and front edges flanged outwardly; and rigid supporting-hangers adapted to run on a track.

6. In combination, a sheet-metal door having its top, bottom and front edges flanged outwardly; rigid hangers for supporting the door and the track upon which the hangers are adapted to run, the door being so mounted that it travels in the plane which it occupies when closed.

JAMES M. HOPKINS.
